COMPRESSOR UNLOADER

Bruno V. E. Nordberg, Milwaukee, Wis., assignor
to Nordberg Manufacturing Company, Milwaukee, Wis., a corporation of Wisconsin

Application October 9, 1937, Serial No. 168,266

14 Claims. (Cl. 230—31)

This invention relates to compressors and particularly to unloading means therefor.

In a prior application, Serial No. 49,624, filed November 13, 1935, I describe and claim an unloading mechanism applicable particularly to compressors having automatic valves. According to that invention a master mechanism delivers timed hydraulic impulses to motors which control the closing movement of corresponding inlet valves, the effect of the valve control being to vary progressively the effective displacement stroke of the compressor. The master mechanism was self-contained. It was driven by the crank shaft of the compressor, and not only generated the timed hydraulic impulses, but also developed in an accumulator hydraulic pressure, which under control of a follow up valve responsive to receive pressure, actuated the means to vary the duration of the hydraulic impulses.

The present invention involves similar principles and is subordinate to the prior application. It differs from the prior device chiefly in the means used to generate and time the hydraulic impulses. In the prior device there was a displacement plunger for each valve motor and the commencement of the impulse was timed by varying the closure of a spill back valve. According to the present invention there is a displacement plunger for each valve motor, but no spill back. Instead, the timing of the plunger movements is varied relatively to the compressor crank shaft, so that the impulses commence at different compressor crank-angles.

As is the case in my prior application, I prefer to use valve controlling motors which are biased to no-load position and move to loading position in response to the impulse. Thus the commencement of the impulse marks the closure of the inlet valve and consequently the commencement of the effective working (displacement) stroke. This has practical operative advantages fully developed in my prior application.

The invention will be described as applied to a single cylinder double acting compressor. Such a compressor has two working spaces with inlet valves timed 180° of crank angle apart.

In the drawings:—

Figure 1 is a plan view of a compressor of the type stated, showing the invention applied.

Fig. 2 is a fragmentary section, transverse to the axis of the cylinder, through the center line of one of the inlet valves and its associated unloading motor.

Fig. 3 is a vertical section through the master mechanism, on the line 3—3 of Fig. 6.

Fig. 4 is a horizontal section through the master mechanism on the line 4—4 of Fig. 3.

Fig. 5 is a sectional view, somewhat diagrammatic in character showing the regulating mechanism with the servo motor and controlling valve 5 for setting the regulating mechanism.

Fig. 6 is a section on a reduced scale taken on the line 6—6 of Fig. 4.

Referring first to Fig. 1 the bed of the compressor is indicated at 6, and the frame of the compressor at 8. The crank shaft 9 turns in bearings 11 and 12, and reciprocates a piston in the cylinder 13. The crank, connecting rod, cross-head, piston rod and piston are not visible in the drawings, as the illustrated compressor is of the enclosed type. Being conventional these parts are too well known to require illustration.

The compressor may be driven by any suitable means, but a synchronous motor of the fly-wheel type is preferred and is conventionally indicated at 7.

The intake or suction 14 leads to the inlet valves. There are four such valves, two for the head end, indicated at 15a in Fig. 1, and two for the crank end similarly indicated at 15c. All four 25 inlet valves are identical in construction. The discharge valves, which may be of any suitable type are not visible in the drawings but discharge to connection 16 which leads to receiver 17. The pipe 18 delivers the compressed air to the point 30 of use.

I prefer that both inlet and discharge valves be of the "reed" or "feather" type claimed in the Nordberg Patent, No. 1,570,392, January 19, 1926, and such inlet valves are chosen for illustration. 35 Each inlet valve is provided with an unloader motor whose function is to hold the valve open for variable periods through the initial portion of the discharge stroke in the corresponding working space. Each pair of motors (i. e., those of paired 40 inlet valves) is controlled by a corresponding impulse generator and timer in the housing 19. The drive shaft 21 of this master mechanism is driven from crank shaft 9 at the same angular velocity through sprocket chain 22. Receiver 45 pressure is transmitted by pipe 23 to the pressure responsive element of a timing mechanism in housing 19. There are head end and crank end impulse mechanisms in housing 19 and these are connected by pipes 24a and 24c with the unloader motors of the head end inlet valves and of the crank end inlet valves, respectively.

Referring now to Fig. 2 which shows a head end inlet valve, the construction of all the inlet valves can be explained.

The cylinder 13 is cored to produce a jacket, portions of which appear at 25 and an inlet passage 26 leading to the inlet valves from the inlet connection 14. Seated on rib 27 surrounding inlet port 28 and sealed thereto by gasket 29 is the grid-like valve seat member 31. This is held down by the inverted V-shaped yokes 32 engaged by studs threaded in bonnet 15h (and not visible in Fig. 2), a construction for which 5 no novelty is here claimed. The guard grid 33 underlies the seat and is rigidly spaced therefrom, as shown, the bars of the grid overlying the slot ports in the seat and confining the valve leaf assemblies, each of which comprises a long 10 narrow valve plate 34 and associated bow-spring 35.

To unseat the reed valve elements 34 during the unloading operation, there is provided a yoke 36 having two toothed comb elements 37. The 20 teeth of the elements 37 project through the slot ports in seat 31 and in their inner position toward the axis of the cylinder hold all the reed valves 34 unseated. The yoke 36 is carried on a reciprocable stem 38 guided in a hub 39 25 integral with the bonnet 15h.

Fixed on the upper end of stem 38 is a rectangular yoke 41 whose upper end in the retracted (loading) position engages a combined stop and spring seat 42. The spring seat is 30 mounted on the outer neck-like end of a sleeve 43 which is threaded into bonnet 15h, and is centered and held by the apertured cap 44. The compression spring 45 reacts between seat 42 and yoke 41 and urges the stem 38 in a direction to 35 unseat the valves.

The yoke 41 embraces a piston 46 provided with packing grooves and working in a cylinder 47 freely uncircled by the yoke and positioned in bonnet 15h by means of the opposite lugs 48 40 which seat in a counterbore. The sleeve 43 acts to force the lugs downward and clamp the cylinder in place. Inward motion of stem 38 is limited by collision of the outer end of yoke 41 with the outer end of cylinder 47.

The impulse pipe 24h (in the case of the head-end valves) communicates by means of a 45 nipple 49 and port 51 with the working space in cylinder 47 below piston 46. The spring 45 holds the unloader in unloading position except when an impulse is directed through pipe 24h to the space below piston 46. In other words, the inlet valves are normally held open and are allowed to close for chosen periods by the development of hydraulic pressures for such periods 55 in the cylinder 47.

The inlet valve mechanism is thus the same as that described in my prior application in somewhat greater detail.

The mechanism which develops the timed pressure impulses for the head end and crank end inlet valves is shown in Figs. 3-6 and will 60 now be described. Oil will be described as the hydraulic fluid because it is preferred, but without limiting implication.

The shaft 21 of the impulse unit has been described as driven at the same angular speed as the compressor crank shaft by chain 22 (Fig. 1). This chain runs on sprocket 52 (Fig. 4). Shaft 21 and a parallel cam shaft 53, carry identical 65 small sun pinions 54 and 55 (Fig. 5). These do not mesh directly but are connected by larger meshing planet gears 56, 57. A pair of bell cranks 58 and a pair of radius links 59 connected by spacer links 61 carry the idler gears 56, 57, 70 the pins 62 and 63 on which the gears are re-

spectively journaled serving also to hinge the parts 58 and 61 and also 61 and 59 together, as shown.

Obviously angular displacement of bell crank 58 on shaft 21 causes angular displacement of gear 55 relatively to gear 54. More specifically, the gears turn in opposite directions, but shifting of bell crank 58 clockwise (as to Fig. 5) displaces shaft 53 clockwise relatively to shaft 21.

Thus shifting of bell crank 58 in opposite directions causes shaft 53 to be advanced or retarded relatively to the rotation of shaft 21, and is used to change the timing of two cams 64 and 65 (which are fast on shaft 53 and drive the unloader impulse plungers 66 and 67) with respect to crank shaft 9 of the compressor.

Two cams are used because the compressor has two working spaces, and the cams are 180° apart because the working spaces are the opposite ends of this same double acting cylinder.

Adjustment of bell crank 58 is in response to receiver pressure and is effected by a double-acting piston 68 in cylinder 69. Piston rod 71 is connected by link 72 with one arm of bell crank 58. A governor piston 73 is subject to receiver pressure arriving via pipe 23 and port 74, and acts upward on lever 75 fulcrumed at 76 and loaded at 77 (see Fig. 3). Lever 75 is connected by two articulated links 78a, 78b, with one end of combining lever 81. The purpose of 25 two links 78a and 78b will be later discussed, but normally they act as a single link and for present purposes will be so considered. Link 72 and consequently bell crank 58 is connected by link 79 with the other end of combining lever 81. Lever 35 81 is pinned intermediate its ends to a balanced piston distributing valve 82 of the inside admission and outside exhaust type, clearly shown in Fig. 5, and controlling distribution to the two ends of cylinder 69. This valve has the minimum 40 practical lap on the cylinder ports on both inlet and exhaust edges so as to afford a sensitive and responsive control of piston 68, and yet ensure that the piston 68 will be locked by the lap of the valve against yielding to the substantial force reactions transmitted through bell crank 58. This is a well known follow up valve mechanism.

As piston 73 moves up or down under changes in receiver pressure, piston 68 moves down or up (i. e. reversely) and for every position of piston 73 there is a definite corresponding position of piston 68. Thus cams 64 and 65 are angularly advanced or retarded relatively to compressor crank shaft 9 in response to the fall and rise of receiver pressure respectively.

In the embodiment illustrated the crank shaft 9 turns "under", the direction of rotation being indicated by an arrow on Fig. 1, and the arrangement is such that as receiver pressure falls, 60 the cams are advanced. Such advancement has the effect of increasing the loading of the compressor because the impulse plungers act earlier in the compressor displacement stroke and thus permit the inlet valves to close earlier.

Each of the plungers 66, 67 is urged toward shaft 53 by a corresponding coil compression spring 83 or 84 of substantial strength. The plungers 66 and 67 work in cylinders, 85 and 86, whose ends are connected respectively with the 70 tubes 24c and 24h which lead to the crank end and head end unloader motors, as already explained.

Each plunger 66, 67 in its retracted position (see plunger 67, Fig. 3) overtravels an inlet port

87, 88 (see 88, Fig. 3) through which oil enters the cylinder from reservoir 89. Reservoir 89 is in communication with oil tank 91 in which shaft 53 runs, by way of port 92 and passage 93. A 5 strainer 94 carried by closure plug 95, is mounted in passage 93 between tank 91 and port 92.

The displacement of each plunger 66, 67 is greater than the aggregate displacement of the related pistons 46 (there being two pistons 46 10 driven by each plunger), so the unloaders are shifted promptly upon movement of the plunger. The excess liquid is displaced through loaded relief check valves 96, 97 and through passage 98 to an accumulator chamber 99 beneath plunger 15 101 which is loaded by spring 102. A pipe 103 leads from accumulator 99 to the chamber in which valve 82 works, and supplies the pressure fluid (oil) to operate piston 68, and adjust the position of cam shaft 53. Hence the device is 20 wholly self-contained.

Piston 101 in its extreme upper position exposes relief port 104 which delivers through passage 105 to the air separating cup 106 with baffle 107. From cup 106 oil overflows to cup 108 from 25 which it may pass through opening 92 to chamber 89.

The parts are so timed that with the cams 64, 65 in their most advanced setting, plungers 66, 67 will cause retraction of the valve holding 30 combs at the start of the displacement strokes so that the inlet valves close as the stroke starts. Retardation of the cams progressively, causes retardation of the action of the plungers so that the combs are retracted progressively later. In the 35 fully retarded position, the inlet valves are not permitted to close at all.

Since the displacement of the plungers 66, 67 exceeds the displacement of the unloader pistons and since the plungers overtravel the inlet ports 40 87, 88, the plungers exert suction on their back strokes (under the urge of springs 83 and 84), and help to restore the unloader pistons and hence the combs to that position in which they obstruct the closing movement of the inlet valves.

Reference has been made to the use of two 45 links 78a and 78b between pressure responsive lever 75 and combining lever 81. This is really an optional feature permitting the application of means to unload the compressor completely when it stops and maintain it unloaded for a substantial 50 interval after it starts, so that it may come to full speed under no load.

To effect this result it is necessary to shift links 78a, 78b to the dotted line position (Fig. 3) 55 as an incident to stopping, and to restore them slowly to full line position as an incident to starting, so slowly that the compressor attains full speed before it is loaded in any material degree. Various means might be used for this purpose, 60 but a convenient means and one which broadly considered has been used to unload compressors during starting, comprises a pressure motor responsive to pressure in a pressure oiling system. Pressure in such system fades rapidly when the 65 compressor stops and is built up gradually as the compressor starts.

Cylinder 111 has a reciprocating piston 112 connected by rod 113 with the hinge between links 78a, 78b. An annular stop 114 limits outward 70 motion of piston and a coil compression spring 115 urges the piston 112 inward. The working space behind piston 112 is connected by pipe 116 with the oil pressure line leading from oil pump 117. A check valve 118 loaded by a light spring 75 119 opens for rapid flow from the working space,

while a choke 121 limits return flow to a slow rate.

Consequently, when the compressor stops and lubricating oil pressure drops, piston 112 moves rather rapidly inward, raising lever 81 and causing piston 68 to shift to unload the compressor completely. When the compressor starts piston 112 will be slowly forced outward and after a suitable time interval, determined by the size of choke 121, the links 78a, 78b resume the normal 10 position shown in full lines in Fig. 3. In this position the degree of loading depends on the pressure under piston 73.

Failure of lubrication tends to protect the compressor by unloading it. 15

The device, like that of my copending application, generates its own hydraulic impulses and hence is wholly self-contained. It can be applied to existing compressors in a very simple manner. 20

While a particular type of inlet valve has been 25 illustrated, this is merely exemplary, for the invention can be applied to any valve whose movements can be arrested for unloading purposes. Any number of working spaces can be controlled by simple duplication of impulse mechanisms one 30 for and timed to suit the particular space which it serves.

Various other modifications are possible within the scope of the invention. 35

What is claimed is:

1. The combination of a compressor having successive operating cycles, each comprising a suction stroke and a displacement stroke; liquid displacing means for generating successive hydraulic pressure impulses, one for each cycle, said means being capable of developing impulses of uniform duration and at least as long as the duration of the displacement stroke; means for varying the timing of said impulses with reference to the timing of the displacement stroke, 40 whereby the impulses start at variable points in the displacement strokes; and means subject to such impulses for unloading the compressor during the displacement stroke until such impulse is initiated and for thereafter loading the compressor throughout the remainder of such stroke. 45

2. The combination of a compressor having a cylinder, a coacting piston, and an inlet valve; unloading means having two positions, in one of which it renders the inlet valve inoperative and in the other of which it permits the inlet valve to operate; means biasing said unloading means to one of said positions; a pressure motor adapted when under pressure to shift said unloading means to the other of said positions; an impulse 50 piston driven by the compressor and connected to deliver pressure impulses to said motor; and means interposed in the drive between said compressor and said impulse piston and adjustable to vary the timing of the impulse piston relatively to the strokes of said compressor piston. 55

3. The combination of a compressor having a cylinder, a coacting piston, and an inlet valve; unloading means having two positions, in one of which it renders the inlet valve inoperative and 60 in the other of which it permits the inlet valve to operate; means biasing said unloading means to one of said positions; a pressure motor adapted when under pressure to shift said unloading means to the other of said positions; an impulse 65 piston driven by the compressor and connected to deliver pressure impulses to said motor; means interposed in the drive between said compressor and said impulse piston and adjustable to vary the timing of the impulse piston relatively to 70 75

the strokes of said compressor piston; and means responsive to the pressure against which the compressor discharges for adjusting the last named means.

5. The combination of a compressor having a cylinder, a coacting piston, and an inlet valve; unloading means having two positions in one of which it renders the inlet valve inoperative and in the other of which it permits the inlet valve 10 to operate; means biasing said unloading means to one of said positions; a pressure motor adapted when under pressure to shift said unloading means to the other of said positions; an impulse piston adapted to be driven by the compressor 15 and connected to deliver pressure impulses to said motor; and a driving connection interposed between the compressor and said impulse piston, including a gear train of the sun and planet type having a portion displaceable to vary progressively the timing of said impulse piston with relation to the piston of the compressor.

6. The combination of a compressor having a cylinder, a coacting piston, and an inlet valve; shiftable means adapted to obstruct the closing 25 movement of the inlet valve; means biasing said shifting means toward obstructing position; an hydraulic motor serving when subjected to pressure to withdraw said obstructing means; an hydraulic impulse piston adapted to be actuated 30 in timed relation to the compressor piston and having a displacement which exceeds the displacement of the hydraulic motor; means for establishing an hydraulic pressure transmitting connection between the impulse piston and the 35 hydraulic motor; a loaded relief valve permitting flow of excess hydraulic liquid from said connection; and adjustable driving connections interposed between said compressor and said hydraulic impulse piston and adjustable to vary 40 the timed relation between the impulse piston and the piston of the compressor.

7. The combination of a compressor having a cylinder, a coacting piston, and an inlet valve; shiftable means adapted to obstruct the closing 45 movement of the inlet valve; means biasing said shifting means toward obstructing position; an hydraulic motor serving when subjected to pressure to withdraw said obstructing means; an hydraulic impulse piston adapted to be actuated 50 in timed relation to the compressor piston and having a displacement which exceeds the displacement of the hydraulic motor; means for establishing an hydraulic pressure transmitting connection between the impulse piston and the 55 hydraulic motor; a loaded relief valve permitting flow of excess hydraulic liquid from said connection; adjustable driving connections interposed between said compressor and said hydraulic impulse piston and adjustable to vary the timed 60 relation between the impulse piston and the piston of the compressor; an accumulator fed by said loaded relief valve; a fluid pressure servomotor supplied with motive fluid by said accumulator and connected to adjust said driving 65 means; and a pressure operated valve mechanism responsive to the pressures against which the compressor discharges and serving to control said servo-motor.

8. The combination of a compressor having a cylinder and a coacting piston; unloading means 70 for said compressor; an unloader piston for actuating said unloading means; an impulse piston adapted to be actuated in timed relation to the compressor piston and having a displacement 75 which exceeds the displacement of the unloader

piston; means for establishing an hydraulic pressure transmitting connection between the impulse piston and the unloader piston; a pressure accumulator; a loaded relief valve for permitting flow of excess hydraulic liquid from said connection under pressure to said accumulator; an adjustable driving connection between said compressor and said impulse piston; a servo-motor connected to actuate said adjusting means; means responsive to the pressure against which said 10 compressor discharges; a distributing valve for controlling said servo-motor; and means for actuating said valve responsive to the combined effect of said pressure responsive means and the position of said servo-motor, whereby the servo-motor is caused to assume different positions corresponding to the various pressure against which the compressor discharges.

9. The combination defined in claim 7 in which the adjustable driving connection between the 20 compressor and the impulse piston includes a sun and planet gear train whose adjustment effects the timing of the impulse piston with respect to the compressor piston.

10. The combination of a compressor having successive operating cycles; liquid displacing 25 means for developing liquid pressure impulses of uniform duration in timed relation to the operating cycles of the compressor; an adjustable drive train between the compressor and said liquid displacing means for modifying the time relation between the compressor and said displacing means; and an unloading means for the compressor operated by said impulses and serving to unload the compressor to a degree which varies 30 with the timing of the impulses relatively to the compressor.

11. The combination of a compressor having successive operating cycles; liquid displacing 40 means for developing liquid pressure impulses of uniform duration in timed relation to the operating cycles of the compressor; an adjustable drive connection between the compressor and said liquid displacing means for modifying the timing of the liquid pressure impulses with reference 45 to the operating cycle of the compressor; and means responsive to the pressure against which the compressor discharges and operated by pressure fluid derived from said impulses to adjust said adjustable drive.

12. The combination of a compressor of the 50 expandible chamber type adapted to perform successive operating cycles; an unloading device having two positions in one of which it renders the compressor inoperative and in the other of which it renders it operative; means biasing said unloader toward one of said positions; a pressure motor serving when energized to shift said unloader to the other of said positions; an impulse piston operable in timed relation to the 60 cycles of the compressor; means establishing a fluid pressure transmitting connection between said impulse piston and said compressor motor; and a drive train between said impulse piston and said compressor, said drive train including 65 an adjustable element for varying the timing of the impulse piston relatively to the cycles of the compressor.

13. The combination of a compressor of the expandible chamber type having an inlet valve 70 and adapted to perform successive operating cycles, each comprising a suction stroke in which said inlet valve is normally open and a discharge stroke in which said inlet valve is normally closed; an unloading device having two positions in one 75

of which it holds the inlet valve open and in the other of which it permits the inlet valve to operate normally; means biasing said unloader piston toward the first of said positions; a pressure motor serving when energized to shift said unloader to the second of said positions; an impulse piston operable in timed relation to the cycles of the compressor; means establishing a fluid pressure transmitting connection between said impulse piston and said pressure motor; and an adjustable drive between said compressor and said impulse piston and adjustable to cause the impulse generated by said piston to overlap the whole or any desired part of the discharge stroke 15 of said compressor.

13. The combination of a compressor of the expansible chamber type having an inlet valve and adapted to perform successive operating cycles, each comprising a suction stroke in which the inlet valve is normally open and a discharge stroke in which the inlet valve is normally closed; an unloading device having two positions in one of which it obstructs the closing movement of the inlet valve and in the other of which it permits the inlet valve to operate normally; means biasing said unloader to the first of said positions; a pressure motor serving when subject to pressure to shift said unloader to the second of said positions; an impulse piston operable in timed relation to the cycles of said compressor and having a displacement which exceeds the displacement of said pressure motor; means establishing a fluid pressure transmitting connection between the said impulse piston and the compressor motor; a pressure accumulator; a relief valve for delivering excess liquid from said con-

nexion to said accumulator; driving connections between said compressor and said impulse piston, said drive connection including adjustable means for varying the timing of the impulse piston with reference to the compressor cycle, whereby the 5 impulses may be caused to coincide with the whole or any desired portion of the discharge stroke of the compressor; a servo-motor connected to adjust said drive; means responsive to the pressure against which said compressor 10 discharges; and a controlling valve for said servo-motor subject to conjoint control by said pressure responsive means and by the adjusting means for said drive connection.

14. The combination of a compressor having 15 successive operating cycles each comprising a suction stroke and a displacement stroke; liquid displacing means for developing successive hydraulic pressure impulses, one for each cycle, said means being capable of developing such impulses 20 over the entire displacement stroke; control means for varying the point in the displacement stroke at which such impulse is initiated, between a no load position in which it occurs at the end of the displacement stroke and a full load position 25 in which it occurs substantially at the beginning of the displacement stroke; means for unloading the compressor during the displacement stroke until said impulse is initiated and for thereafter loading the compressor through the remainder of 30 the stroke; and means rendered effective by stopping the compressor, to move said control means to no load position and for inhibiting its return to a loading position for a time interval after the compressor is started. 35
